(57) **CLAIM**

I claim the ornamental design for the pet toy, as shown and described herein.

DESCRIPTION

FIG. 1 is a perspective view of the pet toy showing my design;

FIG. 2 is a side elevation view thereof, the opposite side is identical to the side shown;

FIG. 3 is a side elevation view thereof rotated 45 degrees horizontally from the view shown in FIG. 2, the opposite side is identical to the side shown; and,

FIG. 4 is a top plan view thereof, the bottom plan view being a mirror image of the top view.

1 Claim, 2 Drawing Sheets

FIG. 1

FIG. 2

FIG. 3

FIG. 4
